UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

ORDNANCE.

1,355,388.

Specification of Letters Patent. Patented Oct. 12, 1920.

Application filed July 9, 1919. Serial No. 309,785.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Ordnance, of which the following is a specification.

This invention relates to ordnance in which the barrel recoils on slides or guides on the cradle and is particularly applicable to such ordnance in which the barrel has lateral keys or fins and the slides or guides are constituted by grooves in which the said keys or fins work.

According to the invention we provide an improved device for lubricating the slides or guides this device comprising suitably formed pads or other members which are supplied with lubricant and which brush over or move in contact with the bearing surfaces of the slides or guides during the recoil and run-out movements of the gun. The said pads, which may conveniently be made of felt, may be carried by metal structures or castings attached in any suitable manner to each side of the barrel and may be disposed in recesses communicating by passages with lubricant chambers forming part of the castings, these chambers being filled or partly filled with a suitable lubricant such as a mixture of oil and graphite which by gravity is supplied through the said passages to the recesses and thus reaches the pads.

In order that the said invention may be clearly understood and readily carried into effect, the same will now be described more fully with reference to the accompanying drawings in which:—

Figure 1 is a side elevation of a gun with part of the cradle in section, showing more or less diagrammatically a constructional form of our improved lubricating device.

Fig. 2 is a plan of Fig. 1 with part of the gun barrel removed and with part of the cradle shown in section, and,

Fig. 3 is a section taken approximately on the line 3, 3 of Fig. 2 and drawn to an enlarged scale.

A is the gun barrel and A' is the cradle which in the example shown has longi-

tudinal grooves a', a' in which work lateral keys or fins on the barrel, one of these keys being shown at a in Fig. 1. B, B represent the aforesaid metal castings each attached to the barrel by a dowel pin b^o and to the tank D hereinafter referred to by a screw b^{oo} passing through the casting and engaging with a lug on the tank; B', B' are the lubricant chambers which form part of these castings; C, C are the felt pads which are disposed in recesses b, b in the castings B, B, these recesses communicating by passages b', b' with the lubricant chambers B', B'. It will be observed that there are two pads on each side of the gun one of the pads on each side moving in contact with the upper wall of the groove a' and the other with the lower wall of the groove, thereby effectively lubricating both the bearing surfaces with which each key moves in contact. The improved lubricating device is shown as being used in conjunction with ordnance provided with a liquid reservoir or tank D for the recoil or brake cylinder as described in the specification of one of our patent applications filed concurrently herewith, the said reservoir having lateral keys or fins d, d which also work in the grooves a', a'; the aforesaid castings in this case extend from the said reservoir or tank to the keys on the barrel and abut at their front ends against the rear part of the reservoir or tank and at their rear ends against the front surfaces of the keys. The aforesaid pads and the lubricant chamber are preferably as shown arranged at or near the center of the castings and the portions of the latter situated in front of and behind these pads are formed with lateral projections b^x, b^x fitting within the grooves a', a' in the cradle for the purpose of excluding dust from these grooves.

What we claim and desire to secure by Letters Patent of the United States is:—

1. In ordnance, the combination with the gun barrel and the cradle having surfaces on which the barrel slides, of structures carried by the barrel, lubricant chambers forming part of said structures and members which are carried by said structures and are supplied with lubricant from said chambers for automatically lubricating said surfaces during the recoil and run-out movements of the barrel.

2. In ordnance, the combination with the gun barrel and the cradle having surfaces on which the barrel slides, of structures connected to the barrel one on each side thereof, 5 lubricant chambers forming part of said structures, absorbent pads which are supplied with lubricant from said chambers and which move in contact with said surfaces on the cradle during the recoil and 10 run-out movements of the barrel, and means for carrying said pads in said structure.
3. In ordnance, the combination with the gun barrel, lateral keys on the barrel, and the cradle having longitudinal grooves in 15 which said keys work, of structures connected to the barrel one on each side thereof, lubricant chambers forming part of said structures, absorbent pads of which some are in contact with the upper walls of said 20 grooves and the others are in contact with the lower walls and which are supplied with

lubricant from said chambers and means for carrying said pads in said structures.

4. In ordnance, the combination with the gun barrel, lateral keys on the barrel, and 25 the cradle having longitudinal grooves in which said keys work, of structures connected to the barrel one on each side thereof, lubricant chambers forming part of said structures, absorbent pads of which some 30 are in contact with the upper walls of said grooves and the other are in contact with the lower walls and which are supplied with lubricant from said chambers, means for carrying said pads in said structures and 35 lateral projections on said structures extending from said pads to the keys on the barrel and fitting within the grooves in the cradle.

In testimony whereof we affix our signatures.

ARTHUR TREVOR DAWSON.
GEORGE THOMAS BUCKHAM.
